UNITED STATES PATENT OFFICE.

BRUNO MOROSCO, OF NEW ORLEANS, LOUISIANA.

PAPER WINDER.

Application filed September 10, 1926. Serial No. 134,690.

My invention consists in a new and useful improvement in paper winders and is designed to provide a device for winding paper rolls suitable for use in barbers' chairs. The 5 device embodying my invention, hereinafter fully described, constitutes an improvement over the device described and claimed in United States Patent Number 1,553,873, granted to me on September 15th, 1925. The 10 particularly novel and useful feature of my improved device is the combination of means for supporting the supply roll of paper and the means for winding the individual paper rolls, the latter means being provided with 15 a novel form of spindle and winding means therefor.

In the drawings filed herewith, I have illustrated one specific embodiment of my invention, but it is to be understood that I do 20 not consider my invention limited to said specific embodiment but refer for its scope to the claims appended hereto.

In the drawings:—

Fig. 1 is a side elevation of my device.

25 Fig. 2 is an end elevation of my device.

Fig. 3 is a vertical section of a portion of the spindle and winding means therefore.

My device, as illustrated in the drawings, 30 comprises a frame 1 which may be suspended from hooks through suitable holes 2, for carrying the supply roll of paper upon the roller R held by pins 3 in the slots 4 of the frame 1. Suitably attached at the bottom of the frame 1 is the cylindrical receptacle 5 having a longitudinal opening 6 on its front, and end walls 7 and 8 provided with aligned 35 bearings 9 and 10. Slidably received in the bearing 10 is the spindle 11 having therein a longitudinal groove 12, and on its outer end beyond the wall 8 a pull ring 13, and on its inner end in the slot 12 a female 40 socket 14. Suitably mounted for rotation in the bearing 9 is the stub shaft 15 provided with the circumferential groove 16 into which 45 projects the pin 17 threaded through the bearing 9. The stub shaft 15 is provided on its inner end with a tongue 18 having on its end a male head 19 which is received into the female socket 14 when the spindle 11 is 50 placed in operative position. The stub shaft 15 is also provided upon its end outside of the bearing 9 with a gear 20 with which meshes a gear 21 suitably mounted upon the frame 1 and provided with a crank handle 22. The 55 receptacle 5 is provided upon the lower edge

of the opening 6 with a cutting edge 23, and is also provided in its rear wall with finger holes 24.

From the foregoing description of the details of construction of my device, its use will 60 be obvious. When the parts are related as indicated in the drawings, the supply roll of paper being upon the roller R, the free end of the paper roll is inserted into the groove 12 of the spindle 11, the spindle 11 is rotated 65 by the crank 22 and gears 21 and 20, the paper being thus drawn from the supply roll on the roller R and wound upon the spindle 11. This process is continued until sufficient paper is wound upon the spindle 11 70 to fill the receptacle 5 which is of such size as to receive the desired quantity of paper to provide a roll of paper suitable for a barber's chair. When the roll upon the spindle 11 is completed, the rotation of the 75 spindle 11 is reversed to release the end of the roll from the groove 12, and the spindle 11 is then withdrawn from the receptacle 5 by the ring 13. The paper forming the roll in the receptacle 5 can be severed from the 80 supply roll on the roller R by means of the cutting edge 23, and the roll in the receptacle 5 can then be ejected therefrom by the user inserting two fingers through the holes 24 and pushing the roll outwardly through the 85 opening 6.

Having described my invention, what I claim is:

1. In a paper winder, the combination of a spindle provided with a groove and a female socket in said groove; and a stub shaft provided with a tongue having a male head, the spindle being adapted to spring over the male head on the tongue and receive said head into the socket, when the spindle is slid 95 into operative position.

2. In a paper winder, the combination of a cylindrical receptacle having end walls; aligned bearings in said walls; a stub shaft journaled in one of said bearings and provided with a tongue having thereon a male head; and a spindle slidably in the other bearing and provided with a groove having a female socket therein, the spindle being adapted to spring over the male head on the tongue and receive said head into the socket, when the spindle is slid into operative position.

In testimony whereof I affix my signature.
BRUNO MOROSCO.
